US00D906326S

(12) **United States Design Patent** (10) Patent No.: **US D906,326 S**
(45) Date of Patent: **** Dec. 29, 2020**

(54) **CASE FOR ELECTRONIC COMMUNICATIONS DEVICE**

(71) Applicant: **SPIGEN KOREA CO., LTD.**, Seoul (KR)

(72) Inventor: **Jong Eun Kim**, Seoul (KR)

(73) Assignee: **SPIGEN KOREA CO., LTD.**, Seoul (KR)

(**) Term: **15 Years**

(21) Appl. No.: **29/727,393**

(22) Filed: **Mar. 10, 2020**

(51) LOC (12) Cl. **14-03**

(52) U.S. Cl.

USPC **D14/250**

(57) **CLAIM**

The ornamental design for a case for electronic communications device, as shown and described.

DESCRIPTION

FIG. 1 is a front perspective view of a case for electronic communications device showing my new design; and, FIG. 2 is a front elevational view thereof.

The broken lines throughout the drawing figures depict portions of the case for electronic communications device that form no part of the claimed design.

1 Claim, 2 Drawing Sheets
